UNITED STATES PATENT OFFICE.

EARL K. CLARK, OF MANSFIELD, OHIO, ASSIGNOR TO WESTINGHOUSE ELECTRIC & MANUFACTURING COMPANY, A CORPORATION OF PENNSYLVANIA.

THERMAL PLUG CUT-OUT.

Application filed April 2, 1927. Serial No. 180,465.

My invention relates to thermal cutouts and particularly to thermal cutouts for use in motor circuits for the purpose of opening such circuits under overload conditions.

5 An object of my invention is to provide a thermal cutout of the screw-plug type having relatively low current capacity, for instance, one ampere or a fraction thereof, and which may be adjusted to interrupt the circuit after 10 the overload has prevailed for a predetermined time period.

Another object of my invention is to provide a thermal cutout having the above-noted 15 characteristics wherein the cutout device may be renewed after rupture thereof has occurred, the cutout device comprising a removable composite refill that is adapted to interrupt the circuit under predetermined current conditions by causing separation of 20 parts of the refill.

A further object of my invention is to provide a refill for thermal cutouts that shall be inexpensive to manufacture and which may be readily assembled and in which the capacity thereof may be varied by variations in 25 the length of the heating conductor constituting a part of the refill.

These and other objects that will be made apparent throughout the further description 30 of my invention are attained by means of the apparatus hereinafter described, and illustrated in the accompanying drawings, wherein:

Figure 1 is a longitudinal sectional view 35 through a cutout device embodying features of my invention;

Fig. 2 is a plan view of the device shown in Fig. 1, the cover being removed;

Fig. 3 is a top plan view of the refill; and

40 Fig. 4 is a longitudinal sectional view through the refill, taken on the line IV—IV of Fig. 3.

In copending applications, Serial Nos. 614,379 and 614,381 filed January 23, 1923, 45 and application Serial No. 614,378, filed September 18, 1926, by Maurits J. Sandin and assigned to the Westinghouse Electric and Manufacturing Company of East Pittsburgh, Pennsylvania, thermal cutouts are 50 disclosed having screw-plug housings similar to the housing illustrated in Fig. 1.

My invention relates to an improved form of cutout refill and no claim is made to the specific form of housing illustrated.

The housing for the cutout comprises an 55 insulating casing 5 made of porcelain or other insulating material and having a reduced cylindrical portion 6, surrounded by a metal threaded screw shell or terminal member 7 that engages within a threaded socket 60 or receptacle of the usual type (not shown). The casing 5 is provided with an interior bore 8 terminating in an enlarged chamber 9 for receiving a contact washer 11 that is mounted 65 for longitudinal movement therein.

The reduced portion 6 of the casing is provided with a metal tubular contact member 12 that is retained in position by having its inner end peened outwardly to engage the inner inclined wall of the bore 8, as indicated 70 in Fig. 1.

The washer 11 is conductively connected to the terminal shell 7 by means of an annular flexible metal strip 13 that is riveted, at one end, to the underside of the washer 11 75 and, at the other end, to a conductor strip 14 that extends through a channel 15 in the casing and is welded to the threaded terminal 7. The outward movement of the washer 11 is limited by a strap 16 that is welded to the terminal shell 7 and is provided with an extension 17 that is bent inwardly.

The washer 11 is normally biased to its outermost position by means of a spring 18 disposed within the bore 8 between the annular inner end 19 of the member 12 and the inner end of the insulating sleeve 21 which engages the inner side of the washer 11.

The contact terminal 12 is designed to engage a contact member within the receptacle 90 (not shown) and current is conducted between the terminal 12 and the terminal shell 7 through the medium of a refill 22 that is detachably secured within the casing by means of a screw 23 carried by the terminal 12. 95

Normally, current flows from the terminal 12 through the thermal-responsive cutout or refill 22 to the washer 11 and thence to the terminal shell 7 through the conductor strap 14. When the refill becomes ruptured by 100 reason of overload conditions, the spring 18 forces the washer 11 to its outermost position and thus separates the parts of the refill and interrupts the circuit.

The chamber 9 is closed by means of an annular threaded cap 24 that is screwed upon the enlarged portion of the casing 5 and serves to retain a transparent mica window 25

in closed position. The position of the washer 11 may be observed through the opening 26 in the cover.

Considerable difficulty has been experienced heretofore in providing a cutout refill of fractional-ampere capacity having sufficient rigidity to withstand service conditions.

By reason of my improved form of refill, a heating conductor of ample physical strength may be employed in a fractional-ampere circuit which will cause interruption thereof within a predetermined time period after the occurrence of relatively small overload conditions.

15 The cutout refill comprises a metal disc 27 which may be of any desired thickness and heat-storing capacity. The disc is provided with a central opening for receiving the end of a steel tube 29 that is soldered to the washer, as indicated in Fig. 4, by means of solder 31.

The attached end of the tubular member 29 is provided with a longitudinal slot 32 that registers with a radial slot 33 in the disc 27. The purpose of the slots 32 and 33 is to permit of the assembly of a heating conductor 34 that extends through the tubular member 29 and is coiled, as a helix, about its exterior, as indicated in Fig. 4.

20 The heating conductor comprises a piece of relatively high-resistant wire, such as nichrome, that has a coating of heat-and-current-insulating material, preferably asbestos.

The heating conductor 34 is assembled 25 upon the tubular member 29 by inserting it at the unslotted end and through the bore and the slots 32 and 33 in the tube 29 and disc 27, respectively. The external portion is then helically wound upon the exterior of 40 the tube, as indicated in Fig. 4. The end 36 is then welded to the exterior of the tube to form a conductive connection between them.

Since a relatively long heating conductor 45 may thus be employed, a relatively heavy conductor may be used which is of sufficient strength to withstand the stresses imposed by the spring 18 which tends to separate the tube 29 from the disc 27. A relatively heavy heating wire also possesses a greater overload capacity, enabling the refill to function properly on loads above the ampere capacity of low-rated current devices.

When an abnormal current prevails in the 55 circuit, the heating conductor radiates heat which is transmitted to the metal tubular member 29 which, combined with the heating conductor, constitutes a heat-storage member of considerable thermal capacity. Consequently, a slight increase in temperature in the heating conductor and the tubular member will overcome the cooling action of the disc 27 and the washer 11 and raise the temperature of the solder 31 to the fusing point,

at which time the spring 18 causes the disc 65 27 to be separated from the tubular member 29 with a snap action.

The circuit may be restored by removing the casing or cutout plug from its receptacle, 70 (not shown) releasing the screw 23 from engagement with the end of the conductor 34 to permit of removal of the tube 29 and the heating conductor. A new refill may then be inserted and the screw 23 tightened when the refill has been pressed inwardly sufficient 75 to move the terminal washer 11 to its innermost position, shown in Fig. 1.

While I have shown and described a particular form of my invention, changes may 80 be effected therein without departing from the spirit and scope thereof, as set forth in the appended claims.

I claim as my invention:

1. A composite thermal-responsive refill for 85 a circuit cutout comprising a pair of separable members joined by fusible metal, one of which constitutes a terminal member and the other a tubular heat-storing member, and a heating conductor connected, at one end, to the tubular member and wound about the exterior 90 thereof and having its free end extending through the tubular member and constituting a terminal member.

2. A composite thermal-responsive refill 95 for a circuit cutout comprising a pair of separable members joined by fusible metal, one of which constitutes a terminal member and the other a tubular heat-storing member, and a heating conductor connected, at one end, to the tubular member and wound about the exterior 100 thereof and having its free end extending through the tubular member and constituting a terminal member, the said conductor being coated with a heat-insulating material.

3. A composite thermal-responsive refill for 110 a circuit cutout comprising a pair of separable members joined by fusible metal, one of which constitutes a terminal member and the other a tubular heat-storing member, and a heating conductor connected at one end to the tubular member and wound about the exterior 115 thereof and having its free end extending through the tubular member and constituting a terminal member, the said conductor being coated with current-insulating material.

4. A thermal-responsive refill for a circuit 120 cutout comprising a metal disc having a slot extending inwardly from the periphery thereof, a metal tubular member soldered into the disc and provided with a longitudinal slot registering with the slot in the disc through which a heating conductor within the tubular member may extend exteriorly.

In testimony whereof, I have hereunto sub- 125 scribed my name this 29 day of March 1927.

E. K. CLARK.
